UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR TREATING PETROLEUM OIL.

Application filed April 5, 1923. Serial No. 629,974.

To all whom it may concern:

Be it known that I, CARBON P. DUBBS, a citizen of the United States, residing in the city of Wilmette, county of Cook, and 5 State of Illinois, have invented certain new and useful Improvements in Processes for Treating Petroleum Oil, of which the following is a specification.

This invention relates to improvements 10 in a process for treating petroleum oil, and refers more particularly to a process adapted for the cracking or destructive distillation of oils to produce products having substantially the characteristics of gaso- 15 line.

Among the important objects of the invention are to provide a process in which a constant and positive circulation of the 20 condensate separated out during the refluxing of the oil is effected; to provide a process whereby the height of the dephlegmating unit may be considerably lessened, due to the fact that a positive circulation is caused by a mechanical means interposed in 25 the recycling line.

Fig. 1 is a diagrammatic side elevational view of the apparatus used to crack hydrocarbons under pressure of the evolved vapors.

Fig. 2 is a detailed sectional view of the 30 positive means for recycling the reflux condensate.

While this process is particularly adapted to use in a cracking system, it will function 35 as well in systems in which it is desired to produce a positive flow other than by the force of a sustained head of liquid. Such systems may be for the treatment of liquids under atmospheric or super-atmos- 40 pheric pressures.

Referring to the drawing, the oil to be treated is introduced from any convenient extraneous source through the line 1 and may be charged into the top of the dephlegmator 2 through the pipe 3 and spray 4 positioned in the dephlegmator, or by manipulation of the valves 5 and 6 the entire charge or a portion thereof, may be charged directly to the heating coil through the lines 5 and 8. If charged into the top of the

dephlegmator, the cool incoming oil is utilized as a refluxing medium and is flowed downwardly through the refluxing column 2 in an opposed direction to the heated oil vapors rising therethrough.

The charging stock with reflux condensate separated out in the column 2 will flow down through the dephlegmator leg 2^a and be drawn off through the line 9, which communicates with the pipe 8 leading to the heating coil 10.

The heating coil is mounted in a furnace 11, preferably of the side fired type. The oil on passing through the coil 10 in the furnace is raised to a conversion temperature, and in this condition is directed through the transfer line 12 controlled by the valve 13, and is introduced to the vaporizing or expansion chamber 14. This chamber is equipped with residual drawoff lines 15, controlled by valves 16 and try-cocks 17 controlled by suitable valves, for ascertaining the liquid level maintained in the expansion chamber. The residual substances and unvaporized oil drawn off through the 75 lines 15 pass through the cooler 18 from which they are directed to storage, or for retreatment.

The vapors evolved during the conversion of the oil in the expansion chamber pass off through the vapor line 19 controlled by the valve 20 and are introduced into the lower part of the dephlegmator 2 where they are subjected to a refluxing action. In the refluxing stage, the high boiling point fractions are removed, being carried back for recycling and retreatment with the cool charging stock, or flowing back to be combined with the charging stock if the latter is introduced directly to the heating tubes.

The dephlegmated vapors pass off from the top of the dephlegmator through the pipe 21 regulated by the valve 22, and are subjected to final condensing action in the condenser coil 23 positioned in the water condenser box 24. The discharge end of the condenser coil is connected by means of a line 25 controlled by a valve 26 to a receiving tank 27. This receiving tank is equipped with a pressure gauge 28, a pres-

sure relief valve 29, liquid level gauge 30, and a liquid draw off line 31 which communicates with the suction side of a pump 32, the discharge side of which has a pipe connection 33 controlled by a valve 34 for recycling the distillate back to the top of the dephlegmating column, and there utilizing it as a refluxing medium.

5 A second drawoff valve 35 interposed in 10 the drawoff line 36 tapped into the receiver, supplies a means for removing distillate from the system, when desired.

15 As explained, the process is preferably operated under a substantial pressure of 20 the evolved vapors, a constant pressure being maintained upon the entire apparatus or differential pressures upon the separate portions of the apparatus by controlling the valves interposed in the separate connecting lines.

Such oils may be treated as pressure distillate bottoms, kerosene distillates, gas oil, fuel oil and innumerable other oils utilized as charging stocks for cracking systems.

25 The particular advantage of the system lies in the apparatus shown in Fig. 2 which is positioned in the lower portion of the dephlegmator leg designated as 2^b. This device consists of a propeller 37 mounted upon 30 a shaft 38 vertically positioned in the lower portion of the dephlegmator leg and having suitable bearings 39 and 40, the latter being equipped with a stuffing box arrangement for preventing the leakage of the oil 35 around the shaft. On this shaft is also mounted a pulley 41 which is driven by means of a belt 42 from a pulley 43 mounted upon a shaft 44 of the motor 45. The shafts are supported by a frame member 46, 40 which assures proper alignment and support thereof. It is understood that this propeller shaft may be rotated in any suitable manner, the construction shown being adopted merely to disclose one way of driving 45 this positive recycling means for recharging the liquid reflux back into the heating coil.

By positioning the propeller in the lower part of the dephlegmator leg, it will at all 50 times be totally immersed in the reflux condensate, and in revolving will positively force the liquid downwardly through the leg and out through the drawoff line 9.

In place of a single propeller, a plurality 55 of screw propelling means may be used to assure a more rapid flow of the oil. The pitch of the blades, and the rate of revolution will govern the velocity of the recycled condensate.

60 By interposing positive propelling means of this character in the dephlegmator leg, the height of the dephlegmator may be lowered as the velocity of the recycled condensate is not dependent upon the liquid 65 head maintained in the dephlegmating col-

umn; also a positive recycling means of this character, assures a higher velocity of the recycled condensate than is the result of the maintenance of a liquid head in the column.

I claim as my invention:

1. An oil conversion process, consisting in advancing a stream of oil through a coil in a heating zone wherein it is subjected to a conversion temperature while maintained under a superatmospheric pressure, in passing the highly heated oil from said stream into an enlarged reaction chamber from which no unvaporized oil is permitted to return to said coil, in passing the evolved vapors from said reaction chamber to a dephlegmator, in passing a stream of charging oil in heat interchanging relation with the vapors in said dephlegmator to simultaneously preheat such oil and condense the heavier fractions of the vapors, in advancing a second stream of oil directly to the inlet of said coil, in directing the preheated charging oil and the reflux condensate from the dephlegmator to pressure applying means, and in forcing said preheated oil and reflux condensate under mechanically applied pressure into said advancing second stream of oil to be passed therewith through said coil.

2. An oil conversion process, consisting in advancing a stream of oil through a coil in a heating zone wherein it is subjected to a conversion temperature while maintained under a superatmospheric pressure, in passing the highly heated oil from said stream into an enlarged reaction chamber from which unvaporized oil is withdrawn and never permitted to return to said coil, in passing the evolved vapors from said reaction chamber to a dephlegmator, in passing a stream of charging oil in heat interchanging relation with the vapors in said dephlegmator to simultaneously preheat such oil and condense the heavier fractions of the vapors, in advancing a second stream of oil directly to the inlet of said coil, and in directing the preheated charging oil and the reflux condensate from the dephlegmator in a stream moving under applied mechanical pressure into said advancing second stream of oil to be passed therewith through said coil.

3. A continuous process of oil conversion, consisting in heating a stream of oil in a coil disposed within a heating zone to a cracking temperature, in directing the heated oil from said coil into an enlarged zone wherein substantial vaporization occurs, in passing the evolved vapors from said zone to a reflux condenser, in passing a stream of oil in heat interchanging relation with the vapors in said reflux condenser to simultaneously preheat such oil and condense the heavier fractions of the vapors, in forcing a second stream of oil under a mechanical

pressure to the inlet of said heating coil, withdrawing unvaporized residual oil from in placing the oil preheated in the reflux condenser and the reflux condensate under an independently applied mechanical pressure, in uniting such preheated oil and reflux condensate with said second stream of oil to pass therewith through the heating coil, in

10

withdrawing unvaporized residual oil from said enlarged zone to be isolated from the system, and in maintaining a superatmospheric pressure on the oil undergoing conversion.

CARBON P. DUBBS.
